UNITED STATES PATENT OFFICE.

FREDERICK W. KRAUSE, OF CHICAGO, ILLINOIS.

PULVERIZING-MACHINE.

SPECIFICATION forming part of Letters Patent No. 268,029, dated November 28, 1882.

Application filed November 21, 1881. (No model.)

To all whom it may concern:

Be it known that I, FREDERICK W. KRAUSE, a citizen of the United States, residing at Chicago, in the county of Cook and State of Illinois, have invented certain new and useful Improvements in Pulverizing-Machines, of which the following is a specification.

My invention relates to that class of machines in which the quartz, rock, slag, or other material to be pulverized is subjected to the action of rapidly-revolving beaters within a cylindrical casing.

The objects of my invention are to provide a more durable and effective lining for the casing of a pulverizing-machine; to protect that portion of the casing next to the feed-orifice, and where most exposed to wear; to provide a revolving spider with beater-carrying arms of such shape that without increase of material they shall offer the greatest resistance to wear; to so construct the beaters and attach them to their carrying-arms that the greatest durability may be obtained; and, finally, to so construct the discharge orifice and spout of the machine that the strength of the lining will be least impaired and the liability of the machine to clog when working upon wet or damp material will be avoided. These several objects of my invention I attain by the improved mechanism illustrated in the accompanying drawings, and hereinafter fully described and particularly claimed.

Figure 1 is a vertical section of the machine on line *ab* of Fig. 2. Fig. 2 is an end view of the same, showing the hopper and feeding mechanism in section. Fig. 3 is a side view of one of my improved beaters detached, and showing the portion of the same adapted to fit upon the revolving beater-carrying arms. Fig. 4 is a view of the reverse side of such beater. Fig. 5 is a sectional view of the beater, taken upon the line *ef* of Figs. 4 and 5. Fig. 6 is a view of the feed-wheel detached. Fig. 7 is a perspective view of two adjoining lining-plates, showing the manner of forming the discharge-orifice therein. Fig. 8 is a longitudinal cross-sectional view through the arms of the spider-wheel. Fig. 9 is a sectional view on line *w y* of Fig. 8. Fig. 10 is a sectional view on line *x z* of Fig. 8.

Like letters of reference indicate like parts in the several views of the drawings.

The cylindrical casing *A*, held upon suitable legs or standards, is constructed of two separable portions, connected by the hinges *g* at 55 that part of the machine which, for convenience of description, I shall denominate the "back," and retained securely in position when the machine is in operation through the medium of the lugs *u* and a bolt or other suitable 60 fastening device. Each of the halves of the casing *A* is composed of a semi-cylindrical plate and two flat semicircular end plates firmly joined together by the angle-irons *a*; or, if desired, the attachment of these plates 65 may be effected by providing either of them—preferably the end plates—with upturned flanges to receive the connecting rivets or bolts.

Within the casing *A* is placed the lining *C*, formed of removable segmental plates, held in 70 position by bolts or rivets *r*³, or by semicircular bands *b*³, bolted to the end plates of the casing in such manner as to form ways, in which the segmental plates are placed, the plates of the upper portion being retained in their ways 75 by set-screws *s*³. My object in making these plates removable is to permit of the ready replacement by new ones of any such as may have become so worn as to be no longer fit for use. The face of these lining-plates is provided with 80 intersecting ribs *c' c'*, forming pyramidal indentations *c*³. By constructing these curved lining-plates in this manner I obtain far greater strength than is possible where simple corrugated or serrated plates are employed, and 85 this, too, without increasing the thickness of the plates, since it is obvious that the intersecting vertical ribs, of curvilinear shape, will effectively avoid the possibility of any lateral breakage. It is to be noted, also, as of especial importance that by means of the several inclined sides of the indentations the lumps of material will be much more effectively pulverized by being caused to rebound violently 90 against each other and in all directions; and, 95 moreover, the force of the blows and consequent strain on the lining will be greatly diminished by reason of the fact that the material does not strike the same squarely, but glances from the inclined surfaces of the ribs. 100

I have found in practice that the portion of the casing nearest the feed-orifice, and which is exposed to the action of the unbroken or but partially broken material, is subjected to the

greatest wear, and in order to protect this portion of the casing I place at such point the protecting-plate H, of substantially the shape shown in Fig. 1. This plate, which is removably secured to the casing by bolts, has in it an opening, h, corresponding with the feed-orifice of the casing, and at its upper portion is enlarged, and at its lower portion, or that farthest from the feed-orifice, is cut away as the necessity for protecting the casing decreases, the lumps having become partially pulverized.

Within the cylindrical casing, and upon a driving-shaft, r, journaled therein, is placed a revolving spider, B, having beater-carrying arms B' in any desired number, preferably four. This spider is made of cast-steel, wrought-iron, or other material of suitable strength for resisting the action of the substance being pulverized, and the arms are formed radially broad and tapering and axially narrow, giving them in cross-section an oval or ellipsoidal form, as shown in detail in Figs. 8 and 9. This peculiar configuration is given to the arms B', that they may possess the greatest possible strength in the direction subjected to strain; that they may present the least surface for wear and offer the least resistance in the plane of rotation; that they may better deflect the material thrown against them, and that a more effective means of attachment for the beater may be provided.

Upon the ends of the arms B' are fixed the beaters D. Each of these beaters is enlarged at d, where subjected to greatest wear, and is provided upon one side with the flanges o and o', forming the recess l, and upon the opposite side with the recess m. Into the recess l of the beater the end of the arm B' is placed, and by the rivets or bolts d² is fastened thereto.

It is to be noted that the flanges o o' serve the twofold purpose of clasping the arm, and thus relieving the bolts or rivets from strain, and of protecting the ends of the arm and the heads of the bolts from being worn away, when in operation, by the action of the material. In order to better subserve this last object, the flange o, which is in advance as the spider rotates, is made to project some distance beyond the arm B'. The recess m similarly serves to protect the washers of the bolts or ends of the rivets from wear.

Upon the side of the casing A, and in substantially the position shown in Fig. 1 of the drawings, is a feed-orifice, and the delivery-hopper F is connected to the machine at this point through the medium of the conduit G. Within this hopper F is placed the feed-wheel E, having compartments h, by means of which definite measures of the material to be pulverized are fed regularly to the machine.

To prevent the clogging of the feed, and consequent breakage of parts, the edges of the wheel E are rounded off, and for like reason the lower side of the hopper F is formed of a thin steel plate, p, held by a suitable bearing in yoke s' and rendered adjustable by the set-screw s². It will be seen that by thus making the plate flexible and adjustable it will readily

yield when any unusual strain from large lumps of material is offered, and will allow such lumps to pass freely into the machine.

In the front of the cylindrical casing, near the top, and in such location that the revolving spider-wheel shall be interposed between the feed-opening and the discharge-orifice, there is formed a discharge-orifice of oval shape, which is fitted with a spout or nozzle, i, the outer portion of which is enlarged, and is provided with an inclined bottom, so that when the material operated upon is wet or damp it cannot rest upon the spout and cause the machine to clog, but by its gravity will fall.

Through the lining C of the casing a discharge-opening is made of a shape corresponding with that in the casing, and I have found it advantageous to bevel the edges of the lining around the opening, so that no wet material can lodge thereon. It will thus be seen that by forming the discharge-orifice of the lining and casing of oval or ellipsoidal shape, and by locating the same remote from the feed-orifice, and by providing it with double-inclined surfaces, the material delivered to the machine becomes thoroughly pulverized and is freely discharged. Such I have found by long practice is not the case in machines having the discharge-orifice extending axially across the same, as the material is liable to be thrown out before thoroughly comminuted; nor is it the case in machines having smaller discharge-orifices without the inclined spout. The discharge-opening through the lining I prefer to form, as shown in Fig. 7, by cutting away a portion of two adjoining segmental plates, as by so doing less danger is incurred of weakening the plates than when the entire opening is made in a single plate.

I have shown and described above but one revolving spider, although several of them may, if desired, be employed, being placed side by side upon the shaft, with their beaters in spiral relation.

The operation of my machine is as follows: Power being applied in any ordinary manner to the shafts of the feed-wheel and of the spider, the material to be pulverized is placed in the hopper, and by the action of the feed-wheel is carried regularly and in definite charges through the delivery-spout into the machine, where it encounters the rapidly-revolving beaters and is thrown violently against the lining, being thereby finely pulverized, and in the end passing out through the discharge orifice and spout.

What I claim as new, and desire to secure by Letters Patent, is—

1. A curved lining plate or surface for rotary pulverizing-machines, having intersecting ribs which form pyramidal indentations, substantially as described.
2. A lining for the cylindrical casing of a rotary pulverizing-machine, formed of curved segmental plates having diagonal intersecting ribs, substantially as described.
3. A lining or grinding plate for pulverizing-

machines, formed of separable plates, said lining being provided with discharge-orifice, a portion of which is cut in each of two adjoining plates, substantially as described.

5. A lining or grinding plate for pulverizing-machines, having a beveled or inclined discharge-orifice, substantially as described.

10. The combination, with the cylindrical casing of a pulverizing-machine, of a protecting-plate having a broad upper portion, provided with an opening corresponding substantially with the delivery-orifice of the casing, and having the curved lower portion of decreasing breadth, substantially as described.

15. A spider for a pulverizing-machine, having tapering radially broad and axially narrow beater-carrying arms, substantially as described.

20. In a pulverizing-machine, the combination, with the driving-shaft, of oval or ellipsoidal beater-carrying arms, substantially as described.

25. The beater of a pulverizing-machine, hav-

ing upon its side the projecting flanges to form a recess or seat for the beater-carrying arms, substantially as described.

9. A beater for pulverizing-machines, having an enlarged end and recessed sides, substantially as described.

10. A beater for pulverizing-machines, having in one piece with the body of the beater the enlarged portion or head *d*, adapted to fit over the end of the carrying-arm, and a side flange, *o*, adapted to fit over and protect the forward edge of said arm, substantially as described.

30. 11. The combination, with the casing of a pulverizing-machine, having a discharge-orifice located with respect to the revolving beater and the feed-opening, substantially as described, of an obliquely-inclined discharge-nozzle, substantially as set forth.
